(57) **CLAIM**

The ornamental design for a beverage reservoir, as shown and described.

DESCRIPTION

Portions of the present disclosure may contain materials which are subject to copyright or trademark protection. The copyright and trademark owner has no objection to the facsimile reproduction by anyone of the patent document or the patent disclosure, as it appears in the U.S. Patent and Trademark Office patent file or records, but otherwise reserves all copyright and trademark rights whatsoever. FIG. 1 is a perspective view of a beverage reservoir, showing our new design;

FIG. 2 is a left side elevational view thereof;

FIG. 3 is a right side elevational view thereof;

FIG. 4 is a front side elevational view of thereof;

FIG. 5 is a cross sectional view thereof taken along line 5-5 of FIG. 4;

FIG. 6 is a back side elevational view thereof;

FIG. 7 is a top, left and front side perspective view thereof;

FIG. 8 is a top, left and back side perspective view thereof;

FIG. 9 is a bottom, left and front side perspective view thereof;

FIG. 10 is a perspective view thereof, in use condition;

FIG. 11 is a perspective view thereof, in another use condition; and,

FIG. 12 is a perspective view thereof, in another use condition.

The broken line features shown in the Figures are for the purpose of illustrating features that form no part of the claimed design and for the purpose of illustrating the environmental structure in which the beverage reservoir design is intended to be used, and which forms no part of the claimed design.

1 Claim, 12 Drawing Sheets
